United States Patent Office

Des. 182,236
Patented Mar. 4, 1958

182,236

SOCK

Samuel Kay, Stamford, Conn., and Alcide O. Cormier,
Laconia, N. H.

Application September 16, 1957, Serial No. 47,753

Term of patent 14 years

(Cl. D47—7)

Fig. 1 is a side view of a sock embodying our new design; and

Fig. 2 is a view of the side opposite that shown in Fig. 1, the toe portion being cut away for convenience of illustration.

We claim:

The ornamental design for a sock, substantially as shown and described.
